UNITED STATES PATENT OFFICE.

CHARLES L. FUSAY, OF NEW YORK, N. Y.

TOOL FOR USE IN GRINDING OR SHAPING IGNITION POINTS.

Application filed March 15, 1924. Serial No. 699,543.

To all whom it may concern:

Be it known that I, CHARLES L. FUSAY, a citizen of the United States, and a resident of the city, county, and State of New York, have invented certain new and useful Improvements in Tools for Use in Grinding or Shaping Ignition Points, of which the following is a specification.

- This invention relates to an improved tool for use in grinding or shaping ignition points and has for its primary object to provide a very simple device by means of which the circuit closing points or contacts of ignition systems, such as are used in the operation of automobiles, may be accurately ground or re-surfaced so as to secure perfect contact between the points and thereby obtain a spark of maximum intensity in the engine cylinders.
- It is another object of my invention to provide a tool of this character which may be advantageously used in the grinding or facing of the points or contacts on the movable arms and also the stationary contacts of the ignition system. In one embodiment of the invention I provide a base or anvil having a longitudinally extending channel and wear plates fixed upon the anvil at each side of said channel. A post is vertically movable in the anvil and urged upwardly by means of a suitable spring. The upper end of this post projecting into the channel has a threaded bore to receive the stem of the stationary points or contact members of the ignition system. There is also mounted in the anvil a vertically adjustable screw and means is provided for pivotally mounting upon said screw the movable contact or point carrying arm of the ignition system so that the end of said arm having the contact thereon may be positioned upon the upper end of said post. The grinding stone is adapted to be moved transversely across the wear plates and in placing this stone in position, the post is forced downwardly against the action of the spring whereby the ignition point or contact member is yieldingly urged upwardly against the stone. By proper manipulation of the stone, the surface of the ignition point or contact may be rapidly evened or worn down until such surface throughout its area is disposed in a plane parallel with the surfaces of said wear plates.
- It is a further object of the invention to provide a tool having the above noted fea-

tures which consists of relatively few parts of simple construction and may therefore be manufactured and sold at comparatively small cost.

With the above and other objects in view, the invention consists in the improved tool and in the form, construction and relative arrangement of its several parts as will be hereinafter more fully described, illustrated in the accompanying drawings, and subsequently incorporated in the subjoined claims.

In the drawing wherein I have illustrated one simple and satisfactory embodiment of the invention and in which similar reference characters designate corresponding parts throughout the several views:

Figure 1 is a vertical sectional view showing my improved tool and having one of the movable contact point carrying arms arranged in position thereon;

Figure 2 is a top plan view, the point carrying arm being omitted and one of the stationary contact members disposed in position to be faced;

Figure 3 is a vertical section taken on the line 3—3 of Figure 2; and

Figure 4 is an end elevation.

Referring in detail to the drawings, 5 designates an anvil or base which may be of any suitable size and shape and is preferably formed from aluminum or other relatively light metal. The upper portion of this anvil is provided with a longitudinally extending channel 6 and to the upper surface of the anvil at opposite sides of this channel and extending the entire length thereof, the wear plates 7, preferably of hardened steel, are secured.

The anvil or base 5 at one side of its central portion is bifurcated or recessed and in the upper and lower parallel portions, a vertically disposed post 8 is loosely mounted in suitable openings for axial movement. This post is normally urged upwardly by means of a coil spring 9, the lower end of which engages the base or anvil 5 and the upper end of which is engaged against a pin 10 which is adjustable in the series of spaced transverse openings 11 formed through said post. This pin contacting with the upper portion of the base or anvil 5 acts as a stop to limit the upward movement of said post. The upper end of the post 8 is further provided with an axially extending threaded bore 12 and in this bore the threaded stem

or shank of a stationary contact point, such as that indicated at C is adapted to be removably engaged.

At one end of the channel 6 the upper portion of the anvil body is provided with a horizontal extension 13 in which a vertically disposed screw 14 is threaded. The upper end of this screw is bifurcated or provided with the spaced lugs or ears 15 which are apertured to loosely receive a pin 16.

In Figure 1 I have illustrated one of the pivotally movable arms A of an ignition system which carries at one end the movable contact point C¹. The other end of this arm is adapted to be disposed between the ears 15, the openings therein receiving the pins 16. When in this position it will be noted that the other end of the arm carrying the contact point C¹ rests upon the upper end of the post 8. By turning the screw 14 to raise or lower the same, the arm A may be disposed in any desired inclination so that the face of the point C¹ will be positioned in the proper plane relative to the surfaces of the wear plate 7.

In the operation of the device as just described, the grinding or abrading stone S shown in Figure 1, is engaged upon the contact point C¹ and pressed downwardly against the action of the spring 9 until the stone contacts with the wear plate 7. The spring 9 is thus compressed and constantly urges the post 8 and the free end of the arm A upwardly, therefore yieldingly holding the surface of the contact point C¹ against the underside of the stone S. By now rapidly reciprocating this stone across and in contact with the wear plates 7, the abrasive action thereof upon the contact point C¹, wears down the face of said point until said face throughout the area thereof is in a plane parallel with the upper surfaces of the wear plates 7. In this manner, the contact points on the several movable parts A of the ignition system may be very easily and quickly mounted and the faces of said contact points properly and accurately faced. In facing the stationary contact points C, which are provided with the threaded stems or shanks, the screw 14 is not used, it being only necessary to thread the shank of the contact point into the bore 12 in the upper end of the post. The face of the contact point would then be properly ground by means of the stone S in the manner above referred to. By adjusting the pin 10 in the transverse openings 11 of the post 8 the spring 9 may be caused to exert any desired degree of upward pressure of the contact point against the surface of the stone.

From the foregoing description considered in connection with the accompanying drawing, the construction, manner of use and several advantages of my improved tool will

be readily understood. It will be seen that the device is very simple in its construction, and may be easily carried in the ordinary tool kit, owing to the relatively small size of the device and the compact arrangement of its several parts. I have above referred to a particular form and construction of the anvil or base, together with a preferred mounting and arrangement of the several co-operating parts which I have found to be entirely satisfactory in practical use. However, it will be apparent that these parts might be otherwise formed and arranged and the essential features of my invention exemplified in other mechanical structures, than that herein described in detail. Accordingly, it is to be understood that I reserve the privilege of resorting to all such legitimate changes in the form, construction and relative arrangement of the several parts as may be fairly embodied within the spirit and scope of the invention as claimed.

I claim:

1. A tool of the character described, comprising a base having a channel in its upper surface and wear plates at each side of said channel, a perpendicular post mounted in the base and adapted to support a contact point on its upper end, and a spring urging said post upwardly above the channel and acting to yieldingly press the contact point against the face of an abrasive member movable upon and across said wear plates.

2. A tool of the character described, comprising a base having a channel in its upper surface and wear plates at each side of said channel, a perpendicular post mounted in the base and adapted to support a contact point on its upper end, a spring urging said post upwardly above the channel and acting to yieldingly press the contact point against the face of an abrasive member movable upon and across said wear plates, and means for varying the tension of said spring and the distance to which said post is projected by the spring above said wear plates.

3. A tool of the character described comprising a base having a channel in its upper surface and wear plates at each side of said channel, a perpendicular post mounted in the base and adapted to support a contact point on its upper end, a spring urging said post upwardly above the channel and acting to yieldingly press the contact point against the face of an abrasive member movable upon and across said wear plates, a vertically adjustable screw mounted in the base in spaced relation to said post, and means for pivotally mounting one end of a contact point carrying arm upon said screw whereby the contact point on the other end of the arm may be positioned upon the upper end of said post.

4. A tool of the character described comprising a base having a channel in its upper surface and wear plates secured upon the base at each side of said channel, a
5 perpendicular post vertically movable in the base and having a longitudinally threaded bore in its upper end to receive the threaded shank of an ignition contact point, a spring urging said post upwardly
10 to normally position the contact point above said wear plates, and a pin transversely ad- justable in the post to regulate the action of said spring and vary the pressure of the contact point against the under face of the stone disposed upon and movable over said 15 wear plates, said pin engaging the base to limit the upward movement of said post.

In testimony that I claim the foregoing as my invention, I have signed my name hereto.

CHARLES L. FUSAY.
